COMBINATION FLEXIBLE BOTTLE AND SCRAPER

George R. Nowak, Oak Park Village, Ill.

Application February 13, 1957, Serial No. 45,123

Term of patent 14 years

(Cl. D58—12)

Fig. 1

Fig. 2

Fig. 3

Fig. 4

Fig. 1 is a side elevational view of a combination flexible bottle and scraper, showing my new design;

Fig. 2 is an end elevational view thereof, taken from the left side of Fig. 1;

Fig. 3 is an end elevational view thereof, taken from the right side of Fig. 1; and

Fig. 4 is a top plan view thereof.

I claim:

The ornamental design for a combination flexible bottle and scraper, as shown.
